COMBINED HOME RECORDING DISK AND STYLUS THEREFOR

Frederick C. Barton, Haddonfield, N. J., assignor, by mesne assignments, to Radio Corporation of America, New York, N. Y., a corporation of Delaware

Application August 15, 1930. Serial No. 475,411

14 Claims. (Cl. 274—42)

My invention relates to phonograph record-tablets and it has particular relation to tablets adapted for home recording and reproduction.

In the use of phonograph records, particularly by persons unfamiliar with record structures and the proper use and handling of the same, it very often occurs that such records are abused and their life greatly shortened either through ignorance or carelessness on the part of the user. For example, it is desirable to use a fibre stylus in the reproduction of certain types of record tablets to prevent injury to the record-grooves and thereby to prolong the effective life thereof, whereas the users may deliberately or inadvertently employ a hard steel stylus without appreciating the possibility of damage.

Another example may be found in record tablets particularly adapted for home recording and reproduction which tablets are usually soft and are made of flexible material or have other peculiar characteristics.

In short, it is essential, in order to protect the record tablets against abuse and to secure the best results that the tablets be initially recorded and subsequently reproduced with the proper stylus in contact therewith.

It is, therefore, an object of my invention to combine a stylus with a phonograph record tablet.

A still further object of my invention is to pack a special stylus into or to package a special stylus with a phonograph record whereby the two co-operating elements may be distributed and sold as a single article of merchandise.

With the above objects in view, and other objects which will become apparent hereinafter, the invention resides in the method of combining a phonograph record tablet and a stylus for use in connection therewith into a single article of merchandise and the structure for effecting the same.

The invention is illustrated by way of example in the accompanying drawing in which:

Fig. 1 is a plain view of a combined phonograph record tablet and stylus therefor.

Fig. 2 is an enlarged fragmentary sectional view on the line 2—2 of Fig. 1.

Fig. 3 is an enlarged fragmentary sectional view similar to Fig. 2 illustrating a stylus combined with a homogeneous type of record tablet.

Fig. 4 is a fragmentary plan view of a modification wherein the stylus is positioned across the center opening normally found in a record tablet or disk.

Fig. 5 is an enlarged fragmentary sectional

view illustrating the dislodging of the stylus from the record disk upon placing the said disk into co-operative engagement with a turntable.

Fig. 6 is an accentuated fragmentary sectional view similar to Fig. 2.

Fig. 7 is an accentuated fragmentary sectional view similar to Fig. 3.

Referring to the drawing reference character 10 designates a phonograph record tablet or disk having a central opening 11, a label area 12 (3) and an area occupied by a spiral groove of predetermined length as indicated at 13.

For the purposes of this invention the record table 10 may be constructed as shown in Fig. 2, comprising an inert fibrous core 14, such as 70 cardboard, blotting paper or the like which is faced on both sides with a sheet or layer of cellulose acetate or nitrate 15 or like material, the said core and cellulose layer being suitably joined together in a manner well known to those skilled in the art. A disk or tablet structure as above set forth may be utilized as one form particularly adaptable for home recording purposes as disclosed in an application by Albertis Hewitt, filed Sept. 6, 1930, Serial No. 30 480,059, and assigned to RCA Victor Company, Inc., wherein a special stylus is used in conjunction with such a record disk for graving a spiral guide groove pre-formed therein in accordance with variable sound or modulated electrical currents.

In accordance with my invention, the record disk 10 is provided with a short, rectangular opening or slot 16 communicating with the central opening 11 for the purpose of accommodating a part or most of the shank of a stylus 17, one end of which preferably the pointed end, extends into the opening 11. The stylus may be retained in the slot 16 in any desired manner. Preferably, for the sake of simplicity and ease in assembly, use is made of the resilient character of the record tablet or disk 10 to frictionally retain the stylus 17 in place in the slot 16.

In preparing the record 10 for the reception of a stylus, the rectangular opening or slot 16 is suitably formed so as to have a width slightly less than the diameter of the stylus. The stylus 17 may then be pressed or forced into the slot 16 by suitable means until the said stylus is below or substantially flush with the plane surfaces of the record disk 10.

In an alternative arrangement, the slot or opening 16 may be formed across the disk or tablet opening 11 as illustrated in Fig. 4. The purpose of locating the slot 16 so that the stylus 110

15 extends into or across the center opening 11 normally in a record disk or tablet is to provide for the convenient and facile removal of the stylus 17 from the record disk or tablet 5 10 at the time of its use. Referring to Fig. 5, it will be readily apparent that by placing the disk 10 on a turntable 18 with the opening 11 of the disk 10 in registration with the turntable spindle 19 and pressing the central portion 12 of the said disk down over the said spindle, 10 the latter will project through the opening 11 and cause the stylus 17 to be either completely displaced or at least sufficiently displaced to be readily and easily removable from its retaining 15 slot 16 in the said record disk or tablet 10.

15 In a record structure such as illustrated, for example, in Figs. 1 and 2, the slot 16 is, preferably, so formed as to have a width slightly less than the diameter of the stylus 17. Consequently, in pressing the said stylus into the slot 20 16, the edge portions 20 of the slot in the resilient surface layers 15 of the disk 10 are momentarily flexed during the entrance of the stylus 17 into the slot 16 and subsequently return 25 to their original position after the stylus has reached the center or core portion 14 of the disk, which portion is easily displaced or urged laterally by the stylus 17.

From the above description, it will be readily 30 apparent that the resilient surface layers 15 provide a suitable means for yieldably and effectively retaining the stylus 17 within the opening or slot 16.

In a homogeneous type of record tablet structure 35 10' as illustrated in Fig. 3, the slot or opening 16 is so formed as to have a width slightly less than the diameter of the stylus 17 in order that the same may be retained in the slot due to its frictional contact with the side walls there- 40 of when forced or pressed thereinto.

Further, in connection with Fig. 3, the stylus 17 is removed from the slot or opening 16 in a manner identical with that disclosed in connection with Fig. 5.

45 The invention having been exemplified by application to a phonograph record tablet or disk, it is to be understood that the disclosed subject matter may be embodied in many other forms than those illustrated and described, and 50 therefore, no limitations of structure are to be imposed on the invention herein set forth except as may be implied from the scope of the appended claims.

I claim as my invention:

55 1. In combination, a phonograph record tablet having a central opening and a second opening extending radially from and communicating with said first named opening, and a stylus disposed and frictionally retained in said second opening.

2. In combination, a phonograph record tablet having a central opening and a slot extending radially from and communicating with said first named opening, and a stylus frictionally held in 65 said slot, said slot being of such length that a portion of said stylus extends into said central opening.

3. In combination, a laminated record tablet comprising an inert core and resilient surface layers, and a stylus imbedded in said core and 70 removably retained therein by said surface layers.

4. In combination, a phonograph record-tablet 75 having a center opening and a stylus, the stylus being carried by the tablet to extend at least

partially into the center opening thereof where- 80 by the act of threading the tablet upon the spindle of a record support causes said stylus to be partially removed from said tablet.

5. In combination, a phonograph record-tablet 85 having a center opening and a stylus, the stylus being carried by the tablet to extend across the center opening thereof, whereby the act of threading the tablet upon the spindle of a record support causes said stylus to be substantially removed from said center opening.

6. In combination, a laminated record tablet 90 comprising an inert core and resilient surface layers, said tablet having a central opening therein and a second opening extending radially from and communicating with said first named opening, and a stylus partly disposed in said second opening and movably retained therein by said surface layers.

7. In a laminated record-tablet provided with 95 a center opening and having a slot communicating therewith for the reception of a stylus, means comprising the outer laminations of said tablet for removably retaining a stylus in said slot.

8. In a laminated record-tablet provided with a center opening and having a slot communicating therewith for the reception of a stylus, means comprising the outer laminations of said tablet for removably retaining a stylus in said slot substantially below the outer surfaces of 100 said record-tablet.

9. A laminated record tablet comprising a core member provided with a slot adapted to receive a stylus, and surface members having 110 slots registering with said first named slot, the edge portions of said surface members which define said second named slots permitting insertion of the stylus into said first named slot and being of sufficient rigidity to retain the 115 stylus therein.

10. In combination, a phonograph record tablet having a central opening and a second opening communicating with said first named opening, and a stylus disposed in said second opening and frictionally retained by marginal portions thereof, a part of said stylus extending into 120 said central opening whereby said stylus is at least partially dislodged upon placing said record tablet upon a turntable spindle.

11. In combination, a laminated record tablet comprising an inert core and resilient surface layers, said tablet having a central opening therein, a slot extending from and communicating with said opening, and a stylus imbedded 130 in said slot and removably retained therein by said surface layers.

12. In combination, a phonograph record tablet having a central opening therein and a plurality of diametrically opposed slots communicating with said opening, and a stylus imbedded 135 in said slots and so extending across said opening as to be ejected therefrom upon the insertion through said opening of a member having a diameter substantially the same as said opening.

13. In combination, a laminated record-tablet comprising an inert core and resilient surface layers, and a stylus imbedded in said core and removably retained therein solely by said surface layers.

14. In a phonograph record-tablet having a center opening, a stylus imbedded therein across said center opening and adapted for use in connection with said record.

FREDERICK C. BARTON. 150
